G. A. BENNETT.
LOOSE LEAF BOOK OR BINDER.
APPLICATION FILED APR. 22, 1919.

1,363,385.

Patented Dec. 28, 1920.

Fig. 1.

Inventor:-
George Alfred Bennett,
By:- B. Amger, Atty.

UNITED STATES PATENT OFFICE.

GEORGE ALFRED BENNETT, OF SOUTH YARRA, VICTORIA, AUSTRALIA.

LOOSE-LEAF BOOK OR BINDER.

1,363,385.

Specification of Letters Patent. Patented Dec. 28, 1920.

Application filed April 22, 1919. Serial No. 292,005.

To all whom it may concern:

Be it known that I, GEORGE ALFRED BENNETT, a subject of the King of England, residing previously at Quatford, Curraweena Road, Glen Huntly, but now at Hillside, 52 Caroline street, South Yarra, both in the State of Victoria, Commonwealth of Australia, (whose post-office address is Hillside, 52 Caroline street, South Yarra, in the State of Victoria, Commonwealth of Australia,) have invented certain new and useful Improvements in Loose-Leaf Books or Binders, of which the following is a specification.

This invention relates to the class of account or other books having interchangeable leaves and commonly known as loose leaf books or ledgers. The invention is, however directed more particularly to a binder for books of this class in which the two halves or sections of the cover are united by two or more flexible thongs or tapes along which one of the halves or sections is adapted to be drawn to or from the other section by the operation of a screw mechanism located within the movable section of the cover, this mechanism being externally operated by a detachable crank handle or key. The advantages of such books have been proved but the use of the screw mechanism for separating or contracting the two halves of the cover is objectionable both on account of the excessive cost which it entails and also its complexity and liability to derangement.

Loose leaf books of a smaller size have also been used in which the two halves of the cover were expanded or contracted along the tapes by hand and locked in desired positions by means of a ratchet mechanism located within one of the cover sections. This ratchet mechanism is, however, also open to the objections above stated and does not allow of a sufficiently tight grip on the leaves of the book.

The object of the present invention is to eliminate all such winding and ratchet mechanism and to provide a cheap, simple and efficient loose leaf book or binder having all the advantages of the type above mentioned, but at a fraction of its cost. A further object of the invention is to provide the binding bars of the device with rubber or other linings or facings having recesses or indentations by which a tenacious suction grip is exerted upon the leaves of the book. Any loss of power in contracting the binding bars tightly upon the sheets and which might be

entailed by the elimination of the screw mechanism above mentioned is thereby amply compensated for. An additional object of the invention is to provide means for accommodating the binding thongs or tapes to leaves having either round or elongated eyelet holes.

But in order that this invention may be better understood reference will now be made to the accompanying sheet of drawings which are to be taken as part of this specification and read herewith.

Figure 1 is a plan view showing the sections of the cover separated, portions being broken away for convenience of illustration. The fastening clips which lock the movable section of the cover in pre-determined positions on the flexible tapes are shown in locked position.

Fig. 2 is a longitudinal section of Fig. 1 taken in the plane of one of the flexible thongs or tapes.

Fig. 3 is a cross section taken on the line A of Fig. 1.

Fig. 4 is a view similar to Fig. 2 but showing the two sections of the cover contracted upon a series of leaves or sheets, and the fastening clip in an unlocked position. The dotted lines show how the tape is buckled or looped to provide a grip for the hands when the cover sections are being drawn together.

Fig. 5 is an enlarged detail view showing one of the binding bars provided with gripping strips having cavities or recesses therein.

Fig. 6 is a view similar to Fig. 5 but showing corrugations in place of the cavities in the gripping strip.

Fig. 7 is an enlarged section taken in the plane of the hinges and showing clearly how the leaves are held between the gripping strips. One of the cover sections is shown closed.

Fig. 8 is an enlarged perspective view of portion of a tubular flexible thong or tape which may be converted into a round shape.

Fig. 9 is a cross section on line B Fig. 8.

Fig. 10 is a perspective view of a core used to convert the tape seen in Fig. 8 to a round form.

Fig. 11 shows the tape converted into a round form by the insertion of a core.

Fig. 12 is a fragmentary view showing portion of a leaf having elongated eyelets.

Fig. 13 shows portion of a leaf having round eyelets.

Fig. 14 is a sectional view showing clearly how the flexible tapes may be converted for use with leaves having round eyelets.

On reference to the drawings it will be seen that the numeral 2 indicates the front section of the cover and 3 the back section thereof. Attached by suitable hinges 4 to the rear edge of each cover section is a wooden or other binding bar 6. These binding bars are lined on their inner faces with gripping strips 7 or 7' of rubber, metal or other suitable material. Formed in the gripping strips are a series of cavities or recesses 8 as seen in Fig. 5 or corrugations 9 as seen in Fig. 6. These corrugations do not extend quite to the end of the binding bar.

Suitably fixed to one of the binding bars are the inner ends of two or more flexible thongs or tapes 11. These tapes 11 may be of leather, fabric or other suitable material and are of a comparatively stiff nature. They pass through slots or openings 12 formed in the other binding bar and thence into channels or slideways 13 formed within the section 3 of the cover. Part of each slideway is preferably open as at 16 to enable the tapes to be gripped when the cover sections are being drawn together. Rollers 14 and 15 are provided to prevent fracture 30 of the cover and enable the tapes to run freely therein.

Attached to the outer ends of the tapes may be metal or other cross pieces 17 which run in grooves 25 formed at the sides of the slideways and retain the ends of the tapes in position.

Located within recesses 20 formed in the cover section 3 are metal plates 18 from which upstand bearings 19. In these bearings are mounted the trunnions 21 of a fastening clip which may comprise a finger piece 22 formed integral with a right angled holding piece 23 adapted to engage and lock the tapes as seen in Figs. 1 and 2.

Preferably, but not essentially, the fastening clips are connected by arms or extensions 24 to a centrally situated catch 26 so that the operation of said catch simultaneously operates both the fastening clips. The catch 26 is adapted to engage a suitable lock 27 which may be provided with a key hole 28 or other suitable means whereby the fastening clips may be locked in a closed position to prevent unauthorized insertion or removal 55 of leaves from the book.

The thongs or tapes seen in Figs. 1 to 4 are in the form shown, particularly adapted for use with leaves 30 having elongated eyelets 29 as in Fig. 12. In some cases, however 60 the leaves are provided with round eyelets such as 31 (Fig. 13). The eyelets in each case being entered by gullets 32. In Fig. 8 it will be seen that the sides of a tubular tape are stitched together by a series of longitudinal stitches 33. Formed at convenient

intervals in one side of the tubular tape are holes or slits 34 to admit cores 35.

Should leaves having round gullets such as 31 be used the tapes may be converted to suit same by cutting the stitches 33 between two or more of the holes 34 and introducing one or more of the cores 35 through the holes or slits and into the tape which then assumes a round form as seen in Figs. 11 and 14. The number of the cores used will depend upon the number of sheets to be inserted in the book as will be fully understood on reference to Fig. 13 of the drawings.

In use the leaves are inserted in the usual manner by entering the thongs or tapes through the gullets 32. Should it be desired to expand the two sections of the cover for the insertion or removal of leaves, the catch 26 is disengaged from the lock 27 and lifted thereby causing the fastening clips to be lifted also and releasing the thongs or tapes. The two cover sections are now simply drawn apart by holding the section 2 or the leaves resting thereon with one hand and pulling the section 3 outwardly along the tapes with the other. The leaves may now be removed or introduced as desired. To contract the halves of the cover and lock the leaves in place, the outer ends of the tapes are moved toward the fastening clips so that a loop is formed in the tape as shown in dotted lines in Fig. 4. By grasping this protruding part of the tapes with the hands and pulling toward the right in the drawings while the cover section 3 is held stationary the two sections of the cover are drawn together until the gripping strips 7 are pressed tightly against the leaves. The fastening clips are now closed and the catch 26 snapped home and if desired locked by a key or the like inserted in the hole 28. The slack outer ends of the tapes may be then pushed outwardly along the slideways so that they lie flat therein as seen in full lines in Fig. 4.

The recesses or corrugations in the gripping strips create a suction against the leaves and cause them to be firmly gripped between the binding bars.

In the drawings an open backed binder has been shown but it will be obvious that if desired a leather or other flexible back may bridge the space between the binding bars to cover and protect the back edges of the leaves. This flexible back may be adapted to telescope within the two sides of the cover in the manner employed in certain known types of loose leaf books.

It will be obvious that various modifications or alterations may be made in the construction above described without departing from the nature, spirit or scope of the invention and it is intended and desired that the foregoing description shall be inter-

preted as covering such legitimate departures.

What I do claim as my invention, and desire to secure by Letters Patent, is:—

5 1. A loose leaf binder comprising two cover sections, flexible means for uniting said sections together on which flexible means one of said sections is slidably mounted by means of channels or slideways in said 10 slideable section to accommodate the flexible means, and rollers on the slideable cover section over which the flexible means pass.

2. A loose leaf binder comprising two cover sections, flexible means for uniting 15 said sections together on which flexible means one of said sections is slidably mounted by means of channels or slideways in said slideable section to accommodate the flexible means, rollers on the slideable cover section 20 over which the flexible means pass, and cross pieces on the ends of the flexible means mounted to run in grooves in the slideable cover section.

3. A loose leaf binder comprising two 25 cover sections, a binding bar hinged to each of said cover sections, one of said bars having a slot, flexible means secured at one end to one binding bar and passing through the slot in the other bar and thence through 30 channels in the cover section to which said other bar is hinged, the said binding bars having their inner faces lined with resilient material provided with recesses.

4. A loose leaf binder comprising two 35 cover sections, a binding bar hinged to each of said cover sections, one of said bars having a slot, apertured tubular flexible means secured at one end to one binding bar and

passing through said slot in the other bar and thence through channels in the cover 40 section to which said other bar is hinged, the said binding bars having their inner faces lined with resilient material provided with recesses.

5. A loose leaf binder comprising two 45 cover sections, a binding bar hinged to each of said cover sections, one of said bars having a slot, apertured tubular flexible means longitudinally stitched together secured at one end to one binding bar and passing 50 through said slot in the other bar and thence through channels in the cover section to which said other bar is hinged, the said binding bars having their inner faces lined with resilient material provided with re- 55 cesses, and cores in said tubular means.

6. A loose leaf binder comprising two cover sections, a binding bar hinged to each of said sections, gripping strips carried by said binding bars, flexible tapes or thongs 60 fixed to the binding bar of one section and passing through the binding bar of the other section into channels or slideways in said last mentioned section, means for retaining the outer ends of the tapes in the 65 slideways, hinged fastening clips carried by the slideable cover section and adapted to engage and grip the tapes, and a catch interconnected to the fastening clips.

In testimony whereof, I have hereunto set 70 my hand in presence of two subscribing witnesses this 27th day of January 1920.

GEORGE ALFRED BENNETT.
